DESIGN FOR A SPRAYER

Earl L. Rockwood, Toledo, Ohio, assignor to
Gifford D. Davis

Application March 2, 1939, Serial No. 83,289

Term of patent 14 years

To all whom it may concern:

Be it known that Earl L. Rockwood, a citizen of the United States and resident of Toledo, in the county of Lucas and State of Ohio, has invented a certain new, original, and ornamental Design for Sprayers, of which the following is a specification, reference being had to the accompanying drawing, forming a part thereof.

Figure 1 is a side elevational view of a sprayer, showing my new design.

Figure 2 is a side elevational view of the spray-

er shown in Figure 1 and taken at 90° from the view shown in Figure 1.

Figure 3 is a view looking upwardly towards the bottom of the sprayer shown in Figures 1 and 2.

The dominant features of my design reside in the portions shown in full lines.

I claim:

The ornamental design for a sprayer, as shown and described.

EARL L. ROCKWOOD.
